Primary Examiner—Sandra Morris

[57] CLAIM

The ornamental design for a chipper/shredder vacuum apparatus, as shown and described.

DESCRIPTION

FIG. 1 is a perspective view of our design for a chipper/shredder vacuum apparatus;
FIG. 2 is a top plan view of the design for a chipper/shredder vacuum apparatus;
FIG. 3 is a bottom plan view of the design for a chipper/shredder vacuum apparatus;
FIG. 4 is the front elevational view of the design;
FIG. 5 is a right side elevational view of the design;
FIG. 6 is a left side elevational view of the design; and,
FIG. 7 is a rear view of the design.
